CLAIM

The ornamental design for hoof care pad, as shown and described.

DESCRIPTION

FIG. 1 is a top, front, right perspective view of a hoof care pad showing our new design;

FIG. 2 is a bottom, front, left perspective view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a front elevation view thereof; and,

FIG. 8 is a rear elevation view thereof.

The broken lines in the drawings depict portions of the hoof care pad that form no part of the claimed design.

The drawings are shaded to indicate contrasting surfaces.

1 Claim, 8 Drawing Sheets
